UNITED STATES PATENT OFFICE.

ARETUS A. WILDER, OF DETROIT, MICHIGAN, ASSIGNOR OF ONE-HALF TO
CORYDON B. PALMER, OF SAME PLACE.

SAFETY ATTACHMENT AND GOVERNOR FOR ELEVATORS.

SPECIFICATION forming part of Letters Patent No. 248,539, dated October 18, 1881.

Application filed September 27, 1881. (No model.)

To all whom it may concern:

Be it known that I, ARETUS A. WILDER, of Detroit, county of Wayne, and State of Michigan, have invented a new and useful Improvement 5 in Safety Attachments and Governors for Elevators; and I declare the following to be a full, clear, and exact description of the same, such as will enable others skilled in the art to which it pertains to make and use it, reference 10 being had to the accompanying drawings, which form a part of this specification.

My invention consists in the combinations of devices and appliances hereinafter set forth, and more particularly specified in the claims.

15 In the drawings, Figure 1 is a view of my apparatus as applied to an elevator. Fig. 2 is a separate view of the liquid and gear chamber with the face-plate removed. Fig. 3 is a side view of my invention. Fig. 4 is a view of 20 the inside of the gear, showing the method of stopping the free run of the cog.

The object of my invention is to provide a simple and reliable governor and safety attachment for elevators and other similar vehicles, which are liable, by becoming detached 25 from their hoisting appliances, to fall or descend too rapidly for the safety of the passengers or freight that is being hoisted.

A represents an elevator; B, the rack-bar, 30 fastened to the sides of the well, through which the elevator passes for the purpose of engaging with the gear-wheel F.

D is a pinion journaled in a chamber, D². D' is a pinion, also journaled in D², situated in 35 such a position as to mesh closely with pinion D. Keyed to the center of pinion D is a shaft, E, which runs out through the chamber D², and at its end is fixed the cog or pinion F. The inside of the chamber D² may or may not be 40 packed on the faces, so as to make a tight joint where the pinions D and D' touch while making a revolution, for the purpose of preventing the liquid from escaping, which is very material.

45 H is a port leading from the space h to the space h'.

I is a valve for regulating the size of the opening through the port H. This valve is preferably in the form of a piston-valve, as 50 shown.

At the extremity of the shaft E is placed the

cog or pinion F. On the end of the shaft and inside the cover of the pinion F is rigidly fastened the collar f, which fits into a bed drilled or otherwise made in the pinion F. In the 55 cavities left between the collar and the outer rim of the pinion are placed loose rollers f', the purpose of which will be hereinafter shown.

The operation of the device can now be readily understood: The chamber and passage H 60 are filled with water, oil, or other liquid. It is apparent now that the pinions D D' can turn only as rapidly as they can force the liquid in the chamber around through the port H. If, therefore, we suppose the elevator is being 65 hoisted up or lowered down, and that the elevator-cable should suddenly break, the elevator would descend only as rapidly as the liquid could be caused to travel around through the port H at the will of the operator. In the event 70 of the valve being closed down tight and the elevator-cable were to break, the loose pinion F would, actuated by the rack-bar B, immediately commence to revolve in the opposite direction, thus causing the rollers f' to run forward and jam between the edge of the collar f and the outer rim of the pinion F, which would then cease to run independently of the shaft 75 E, and which, in turn, would operate the pinions D and D'.

80 By the construction hereinbefore mentioned the pinions D and D' would remain stationary while the elevator was ascending; but in the descent the valve may be regulated so as to allow the elevator to descend at a uniform pace 85 by simply opening the valve wider or closing it, and then, should an accident happen, the same pace would be sustained throughout the descent, and by closing the valve tight the elevator may be stopped at any point.

90 The pinions D and D' should be carefully dressed, so that when they mesh with each other a liquid-tight joint is formed. When in operation, the liquid is by the pinions forced from the cavity h through the port H into the cavity h', thence, by the pistons h' on the other side, through the other port, H', into the cavity h³, or vice versa, without any waste to the liquid.

95 By "cogged pistons" I would not be understood as limiting myself to the particular piston shown on the drawings, but as compreh-

hending any of the various forms of rotary en-
gaging pistons.

I am aware that the hoisting-drum of an ele-
vator has been provided with gearing located
5 in a liquid-chamber and a valve located and
arranged to govern the flow of liquid through
a passage extending from one portion of the
chamber to another, and hence I make no claim
to such an arrangement of parts.

10 o What I claim is—

1. The combination, with an elevator cage
or car provided with a shaft journaled therein,
and having a pinion arranged to mesh with a
rack, of a liquid-chamber, two rotary cogged
15 pistons located in said chamber, one of said
pistons being secured to the shaft, and a valve
for regulating the flow of liquid from the inlet
to the outer ends of the conduit connecting the
opposite sides of the liquid-chamber, substan-
20 tially as set forth.

2. The combination, with two cogged rotary
pistons having motion imparted thereto by a
shaft, rack, and pinion, said pistons being lo-
cated in a liquid-chamber, of a valve and lever
for regulating the flow of liquid from one side 25
of the liquid-chamber to the other, substan-
tially as set forth.

3. The combination, with the cogged rotary
pistons, shaft, rack, and pinion, of a balanced
valve arranged to regulate the speed of the 30
cogged pistons, substantially as set forth.

In testimony whereof I sign this specification
in the presence of two witnesses.

ARETUS A. WILDER.
